UNITED STATES PATENT OFFICE.

RANDOLPH CROMPTON, OF WORCESTER, MASSACHUSETTS, ASSIGNOR TO HIMSELF, GEORGE CROMPTON, EDWARD D. THAYER, AND WILLIAM B. SCOFIELD, OF WORCESTER, MASSACHUSETTS, DOING BUSINESS AS CROMPTON-THAYER LOOM COMPANY, OF WORCESTER, MASSACHUSETTS, A FIRM.

PATTERN MECHANISM FOR LOOMS.

No. 798,764.

Specification of Letters Patent.

Patented Sept. 5, 1905.

Application filed September 30, 1904. Serial No. 226,628.

To all whom it may concern:

Be it known that I, RANDOLPH CROMPTON, a citizen of the United States, residing at Worcester, county of Worcester, State of Massachusetts, have invented an Improvement in Pattern Mechanism for Looms, of which the following description, in connection with the accompanying drawings, is a specification, like characters on the drawings representing like parts.

This invention relates to pattern mechanism used in looms to control the movement of the shuttle-boxes, and has for its object to avoid using long, cumbersome, and heavy chains.

Prior to my invention there have been used with the main and auxiliary pattern-surfaces having ratchet-wheels weighted indicator-levers moved each by its own indicators and connected with and moving pawl guards or shields coöperating with the other ratchet-wheel of the other pattern-surface and the pawl for moving it step by step, and in this way each pattern-surface through said weighted indicator-lever and pawl-shields puts into operation one or another of two pawls, both mounted on separate pins of a vibrating pawl-arm. In accordance with my invention I provide both the main pattern-surface or chain, and the auxiliary pattern-surface or chain, with pawl-shifting indicators, the indicators of each set of said pawl-shifting indicators acting at intervals on heels of said pawl to throw said pawl out of engagement with the ratchet-wheel last moved by it and placing said pawl in position to act by its opposite end at its next stroke to engage and move the other ratchet-wheel and the pattern surface or chain carried by it. The single pawl referred to has besides the end to engage and

move one of the ratchet-wheels a toe that is acted upon by a pawl-shifting indicator carried by the pattern surface or chain then operative when the time arrives that that particular surface or chain should be stopped and the other surface or chain be started. The single pawl has a third arm, thus making a T-shaped pawl that is carried by a pawl-arm.

Figure 1 in plan view shows a sufficient part of a loom with my improvements added to enable my invention to be understood. Fig. 2 is a side elevation (the fingers being

omitted) of the parts shown in Fig. 1. Fig. 3 is a detail showing the pawl-arm and single pawl of peculiar construction. Fig. 4 shows a pawl-shifting indicator of the main pattern surface or chain as having just operated to start the pawl, so that its movement may be completed by a spring to be described. Fig. 5 shows the opposite end of the pawl as having been put in contact with the ratchet-wheel of the auxiliary pattern surface or chain ready to move that ratchet-wheel. Fig. 6 shows the pawl as moving said ratchet-wheel. Fig. 7 shows the auxiliary pattern surface or chain as having started the pawl and caused its retirement from the ratchet-wheel of the auxiliary pattern surface or chain, and Fig. 8 shows the opposite end of the pawl as in position to actuate the ratchet-wheel of the main pattern surface or chain at the next stroke of the pawl-arm.

The framework A, stud A', sustaining the pivoted fingers A², connected by rods A³ with the usual vibrator-lever or other lever of any usual shuttle-box mechanism, such as commonly used in so-called "Crompton" looms, (see United States Patent No. 405,645,) the crank-shaft B, its pinion B', the shaft B², extended thorough a bearing B³ and carrying the notched disks B⁴ and constituting a carrier for the main pattern surface or chain B⁵, comprising links connected by bars a⁴, surrounded by tubes and balls a, constituting pick-suspending indicators, the ratchet-wheel B⁶, the notched locking-wheel B⁷, the locking-lever B⁸, and the shaft C, its ratchet-wheel C', disks C², carrying the auxiliary pattern surface or chain C³, the notched wheel C⁴, and locking-lever C⁵, connected by spring C⁶, are and may be all as usual.

In accordance with my invention I mount on a stud D a pawl-arm D', having two stops d' d² and a stud d³, and an arm D², provided with guides to receive a rod D³, having at its lower end a roller or other stud d⁴, that enters a cam-groove d⁵ in a disk D⁶, fast on a short shaft D⁷, having at its opposite end a toothed wheel D⁸, driven by the pinion B', said rod being provided with a collar d⁹, and between said collar and the upper guide a spring d¹⁰ is interposed. The stud d³ receives the novel pawl E, shown as T-shaped, the same pre-

- senting a depending leg e and two rigid arms $e' e^2$, the opposite ends 2 3 of which act in one or the other position of said pawl on its stud to engage either the ratchet-wheel B^5 and 5 turn the main pattern surface or chain B^4 or the ratchet-wheel C' of the auxiliary pattern surface or chain C^3 . The opposite end of the top cross-bar of the pawl has extended therefrom oppositely - extended heels 4 5. 10 The heel 4 is extended over the main pattern surface or chain B^4 , so that it is acted upon at intervals by pawl-shifting indicators 6, (any desired number,) carried by said pattern-surface. The heel 5 is extended (see Fig. 1) to 15 cross over the auxiliary pattern surface or chain C^3 and to be acted upon at suitable intervals by auxiliary pawl-shifting indicators 6^x , shown herein as longer projections of the chain C^3 , the shorter projections serving as 20 pick-repeating indicators. The lower end of the pawl is adapted to be engaged by a spring-controlled radius-bar f , pivoted at 7 on the pawl-arm and connected operatively with the pawl by a pin 8 on one entering a slot 10 in 25 the other, the pin being shown as carried by the pawl. The bar has a pin h , with which is connected a spring 12, and the lower end of the spring is attached to a stud 13.
- In operation let it be supposed (see Figs. 1 30 and 2) that the end 2 of the pawl E is in position to engage the ratchet-wheel B^5 and turn the pattern-surface B^4 , it operating to control the fingers A^2 . These figures show the pawl-arm and pawl as having completed 35 their strokes to the left, the spring 12 through the bar f acting on the pin 8 and holding the end 2 of said pawl in contact with said ratchet-wheel, the end 3 of the pawl then occupying its inoperative position and with the auxiliary pattern surface or chain at rest. The 40 spring d^7 acts yieldingly to turn the pawl-arm in the direction to turn the pattern-surface. As the pawl-arm D' is moved to the right, Fig. 2, by the cam-groove d^5 the heel 45 4 will meet one of the pawl-shifting indicators and the pawl will be turned about the stud d^3 for a distance (see Fig. 4) sufficient to cause the pin 8 in the slot 10 to start the radius-bar to the left until the pin h at the 50 upper end thereof passes a line cutting centrally the said stud, the pin 8, and the fulcrum 7 of the bar, when the stretched spring 12 acts immediately to move the radius-bar and cause it, acting on the pin 8, to further 55 turn the pawl E into the position Fig. 5, with its end 3 in position, as the pawl-arm is moved by the cam-groove d^5 from the position Fig. 4 into the position Figs. 5 and 6 to turn the auxiliary pattern-chain. As shown in the 60 drawings, the heel 5 at one end of the pawl will fall at the rear of the pawl-shifting indicator 6^x of the auxiliary pattern surface or chain, and the pawl in the position Figs. 5 and 6 will continue to move the auxiliary pattern 65 surface or chain at each stroke of the pawl-

arm until another pawl-shifting indicator on the auxiliary pattern surface or chain arrives in position to act on the heel 5, as in Fig. 7, when said pawl will be started, as in Fig. 7, and its movement will be completed through 70 the spring 12, as in Fig. 8. So long as the pawl remains in the position Figs. 5 and 6 the main pattern surface or chain will remain at rest, and consequently the distance between one and the next pawl-shifting indicator on the auxiliary pattern-surface will indicate the 75 number of picks that may be taken from any bar a^x of the main pattern-surface, having the pick-suspending indicators a .

I believe that I am the first to employ one 80 and the same pawl to actuate both the ratchet-wheel of the main pattern-surface and of the auxiliary pattern-surface and the first to control one and the same pawl by pawl-shifting indicators carried by two pattern surfaces 85 or chains, and while the means shown herein illustrates one good and operative form of my invention I desire it to be understood that my invention is not to be limited to exactly the construction of device herein shown, but I 90 include any means within the scope of the claims, however constructed, for effecting the results set forth in the claims.

I have designated the rolls a on the main pattern-surface as "pick-suspending indicators" and the short links of the auxiliary pattern-surface as "pick-repeating indicators," and each pattern-surface has its own pawl-shifting indicators.

Having described my invention, what I 100 claim as new, and desire to secure by Letters Patent, is—

1. In a loom, a main and an auxiliary pattern-surface having pawl-shifting indicators, and a pawl having two working ends and heels, 105 the latter being adapted to be acted upon directly by the pawl-shifting indicators of either pattern-surface to cause the pattern-surface having the pawl-shifting indicator that is operative to move the pawl, to remain temporarily at rest while the pawl continues to move the other pattern surface or chain.

2. In a loom, a carrier having a ratchet-wheel, a main pattern-surface mounted on said carrier and having pick-suspending and pawl-shifting indicators, and a pawl having at one end a heel and a portion to engage said ratchet-wheel, said heel being acted upon by a pawl-shifting indicator when it is desired to leave 115 at rest the pattern-surface, while a pick-suspending indicator of said chain is used a plurality of times.

3. In a loom, a main and an auxiliary pattern-surface, the former having pick-suspending indicators and pawl-shifting indicators, 125 the latter having a series of pawl-shifting indicators and pick-repeating indicators, combined with a single pawl, one end of which operates to turn the main pattern-surface, and the opposite end of which operates to 130

turn the auxiliary pattern-surface, the acting end of the pawl when meeting and being acted upon directly by a pawl-shifting indicator of either pattern-surface being turned to be 5 disengaged from the pattern-surface that said pawl was then moving and being put into engagement with and to move the other pattern-surface.

4. In a pattern mechanism for looms, a main 10 and auxiliary pattern-surface each having a ratchet-wheel, and presenting pawl-shifting indicators, a pawl-arm and a single pawl carried thereby and adapted to be acted upon at its opposite ends by the pawl-shifting indicators of one or the other of said pattern-surfaces to cause the then inactive end of said pawl to engage the ratchet-wheel of and move 15 the other pattern-surface.

5. In a pattern mechanism for looms, a main 20 and auxiliary pattern-surface, each having a ratchet-wheel and each carrying pawl-shifting indicators, of a pawl-arm, means for moving the same, and a double-ended pawl having its ends shaped to engage each ratchet-wheel, and having a heel at each end to be acted upon by each pawl-shifting indicator to cause the pawl to be turned on said pawl-arm that its opposite end may engage in turn the ratchet-wheel of the other pattern-surface. 25

6. In a pattern mechanism for looms, a main 30 and auxiliary pattern-surface, each hav-

ing a ratchet-wheel and each carrying pawl-shifting indicators, of a pawl-arm, means for moving the same, and a double-ended pawl having its ends shaped to engage each ratchet-wheel and having a heel at each end to be acted upon by each pawl-shifting indicator to cause the pawl to be turned on said pawl-arm that its opposite end may engage in turn the ratchet-wheel of the other pattern-surface, 35 and means to complete the turning of said pawl and retain the same in engagement with the ratchet-wheel until said pawl is again engaged by a pawl-shifting indicator.

7. In a multiplying mechanism for drop-box looms, a plurality of pattern-surfaces, a common actuator for both surfaces, said actuator being changed by a pawl-shifting indicator of one surface and made to actuate the other surface. 40

8. In a multiplying mechanism for drop-box looms, a plurality of pattern-surfaces having pawl-shifting indicators and a pawl, said indicators acting directly on said pawl to suspend the operation thereof. 45

In testimony whereof I have signed my name to this specification in the presence of two subscribing witnesses.

RANDOLPH CROMPTON.
